UNITED STATES PATENT OFFICE.

ISAAC SIPPILI, OF NEW YORK, N. Y.

DESIGN FOR A BUTTON.

SPECIFICATION forming part of Design No. 20,216, dated October 21, 1890.

Application filed August 13, 1890. Serial No. 361,938. Term of patent 7 years.

To all whom it may concern:

Be it known that I, ISAAC SIPPILI, a citizen of the United States, and a resident of the city of New York, in the county of New York and 5 State of New York, have invented a new Design for Buttons, of which the following is a specification.

In the accompanying drawing, forming a part of this specification, a face view of my 10 new design for buttons is shown.

The leading feature of my design consists in a circular button having thereon a representation of the United States flag, a series of stars semicircularly set in the upper portion 15 of the design, and a semicircular space in the lower portion adapted to receive suitable

words, completing the circle around the flag.

A represents the United States flag; B, the stars; C, an ornamental circle, and D the flag-staff.

Having thus described my design, I claim 20 as new and desire to secure by Letters Patent—

The design for a button, as herein shown and described.

In testimony that I claim the foregoing as my invention I have signed my name in presence of two subscribing witnesses.

ISAAC SIPPILI.
